UNITED STATES PATENT OFFICE

FRANK E. PFEIFFER, OF DAYTON, OHIO, ASSIGNOR TO THE EGRY REGISTER COMPANY, OF DAYTON, OHIO, A CORPORATION OF OHIO

AUTOGRAPHIC REGISTER

Application filed January 2, 1929. Serial No. 329,701.

My invention relates to autographic registers.

The object of my invention is to provide an autographic register employing a plurality of superimposed sheets, which must be accurately aligned and ejected.

It is, in particular, my object to provide such an autographic register by which the sheets are moved to a new writing position 10 a predetermined distance, the moving means is then rendered inoperative by an aligning means using the file punch holes in the sheets for that purpose; and then the sheets are ejected by reengagement of the ejecting 15 means to final position where they are held clamped for writing upon them.

It is my especial object to provide a novel form of aligning pin which, under no circumstances, can stop the sheet from moving 20 outwardly in the direction the sheets are ejected from the machine or stored within the machine.

It is a further object to provide a machine which is of such construction that it 25 might be employed for any lengths of forms by a change of a single cam, and gears.

It is a further object to provide a novel 30 form of detachable sheet spreading means to provide for free movement of the sheets relative to one another; the minimum of drag between the sheets; and between the sheets and the carbon interleaves; and to insure ready alignment by reason of the free movement of the sheets with respect to 35 each other and the carbons when the pins are effecting the aligning of the sheets by insertion into the file punch holes.

By having the pins of my invention, which are only adapted to engage the forward edges of the holes of the sheets for aligning purposes, I eliminate all the difficulties of the sheets being torn against the pins when the pins are used to hold the sheets in alignment during the writing operation as with my invention the sheets are held in position by the clamping of the feeding rollers during the period of the writing operation.

It is a further object to provide independent storage boxes for the packed stationery

which is placed in the register in folded condition as the source of supply and one sheet of which may be likewise stored in another compartment after the record has been written upon it.

It is a further object to provide an adjustable storage compartment to accommodate the size of the compartment to varying types and sizes of stationery so that I am able to provide a machine that is universal for the various commercial lengths of stationery that are accepted as standard practice in the autographic register trade.

It is a further object to provide means in which the ejecting means for the sheets will travel at a more rapid rate than the aligning means so as to pull the sheets away from the aligning means during the beginning of the ejecting operation so that the aligning means cannot tear the sheets.

Referring to the drawings:

Figure 1 is a section through the register on the line 1—1 of Figure 5;

Figure 2 is a top plan view of the register with the cover lifted and the several 75 sheets of paper and carbon broken away to show their interleaved arrangement with the detachable celluloid spacer strips therebetween;

Figure 3 is a section on the line 3—3 of 80 Figure 2;

Figure 4 is an enlarged sectional view showing the exact arrangement of the spacers of celluloid, their method of attachment and mounting and the interleaving 85 of the carbons and the paper;

Figure 5 is a top plan view of the register with the writing table and cover both removed;

Figure 6 is a section on the line 6—6 of 90 Figure 5;

Figure 7 is a section on the line 7—7 looking in the direction of the arrows of Figure 5 showing the exact arrangement of 95 the cams and gears;

Figure 8 is a section on the line 8—8 of Figure 5 showing the position and construction of the parts at the time the aligning pins have been brought into final aligning 100

position and the rollers are in clamped position.

Figure 9 is a section on the line 9—9 of Figure 5;

5 Figure 10 is a diagrammatic view of the feeding rollers, paper sheets and aligning pin in the feeding operation by which the paper is fed out between clamped rollers practically its entire length up to the time 10 the aligning operation starts;

Figure 11 is a second stage of the operation at which time the rollers have been spread and the holes in the paper sheets have been brought to a position where they 15 can be engaged by the aligning pins for the purpose of alignment;

Figure 12 is a similar view showing the aligning pins just about to enter the file punch holes;

20 Figure 13 shows the final stage of the operation of the parts where the rollers are clamped together, the pins are in the holes having aligned the sheets, and the sheets are being held by the clamped rollers for writing purposes;

Figure 14 is a top plan view of one of the aligning pins.

Figure 15 is a section showing the parts in position with the rollers spread and pins 30 about to enter.

Referring to the drawings in detail, the register is composed of side walls 1 and 2 mounted upon a base 3. 4 indicates the rear wall. Upon the rear ends of the side walls 35 there is hinged the cover 5 having a writing opening 6. Also hinged at the rear end of the side walls is the writing table 7.

The forward end of the register is closed by an adjustable detachable storage cabinet 40 comprising side walls 8 and an extreme end wall 9. Within this detachable storage cabinet is an upstanding aligning guard for the record sheet designated 10. The attachment of the adjustable detachable storage compartment to the front end of the register 45 is effected in any desired manner. The exact position of the aligning guard 10 is determined by the set screws 11 in the holes 12 of the bottom of the storage compartment. A storage lid 13 is pivoted on the 50 transverse rod 14 carried in the side walls of the storage cabinet. From this lid depends the swinging guide fingers 15. The lid is supported in closed position by the 55 studs 16 on the side walls of the storage compartment.

In order to form the rear wall of the storage compartment I provide a record sheet 60 guide formed preferably of one piece of sheet steel. This guide is composed of a downwardly directed portion 17 proceeding towards the front of the register, a rearwardly and downwardly directed portion 18 proceeding diagonally, a horizontally disposed portion 19 directed to the rear of the regis-

ter, and a downwardly extending portion 20 attached by the set screws 21 to the bottom of the register, thus forming the rear wall of the storage compartment.

The exact rearward position of the record 70 sheets as they are packed in the storage compartment is determined by the adjustable rear aligning plate 22 as it is adjusted in position by the set screws 23 in any one of the several holes 24 in the bottom of the 75 register.

The pack of record sheets, as indicated in Figure 1, is designated 25. These sheets are fed from the storage pack at 26 in the storage compartment, which is formed by the 80 detachable storage compartment comprising the side walls 27 and the rear wall 28 that are mounted within the main walls of the register. Thus, the pack can be kept in exact alignment laterally by having a detachable compartment which exactly fits the width of paper that is to be used in the machine but other compartments can be employed of different sizes all within the standard machine if a different width of paper 85 is to be employed, thus enabling me to maintain the major portion of the machine in standard form for quantity production at greatly reduced cost, while making available such a machine to varying widths and 90 lengths of forms, as will be hereinafter described.

The front wall of this rear supply storage cabinet is formed by the same sheet steel member which is used as the rear wall of 100 the record storage cabinet.

It will be noted that the sheets, which are brought up from the storage supply pack 26, are carried beneath the guide plate 29 under the spring fingers 30 carried thereby which maintain the paper under a gentle tension for insuring perfect alignment as the sheets are otherwise positively held during the writing operation at the forward end by the clamping ejecting rollers.

110 The sheets are then further spread and maintained in proper predetermined position by a plurality of interleaved celluloid spacer strips 31 that are mounted through enlarged eyes 32 and slots 33 on the studs 34 carried by the writing table 7. This arrangement will be seen in Figures 2, 3 and 4. The carbon paper which is interleaved between the paper sheets is supplied by the roll of carbon paper 35 carried in the carbon storage compartment 36, the top of which 115 is closed by the usual lateral projection of the register cover not here shown in detail.

The size of the carbon can be varied by the positioning of the yielding spacer 36 120 mounted on the carbon supporting rod 37 and positioned by the collar 38 through a screw or bolt 39 in any one of the holes 40 so that carbon paper may be provided of the exact width desired according to the 125

length of the printed form which may be employed in this machine.

Turning to the operating mechanism, it will be understood that the paper sheets have been fed between the ejecting rollers, the details of which are described herein-after.

The operating handle of the register is designated 41 and operates the handle shaft 42. This is the common source of power for all of the ejecting and aligning operations; the handle is designed to pass through a complete cycle of operations and when it does so it comes to rest against the movable stop 43 which can be moved out of stopping position by the finger of the operator grasping the handle in the usual manner.

This operating shaft 42 carries on it a master gear 44 and a spreading cam 45.

This spreading cam engages the cam follower arm 46 which is provided with a nose 47 and an extended finger 48 which abuts against the arm 49 that is carried on the cam shaft 50. This cam shaft extends through the lifting plates 51 on either side of the register which are yieldingly held by the spring 52 in their lowered position to cause the upper roller to remain in its lower clamping position yielding normally. The bracket 53 on the side walls 1 or 2 of the register serves as the support for such lifting plates in their lowered position. The stud 54 is carried in the lower ends of these plates 51 and also abuts through the spring 52 and the stationary bars 53 on the side walls of the register. The cam shaft 50 which passes through these lifting plates is provided with cam surfaces 54^a and is adapted to be independently actuated by the stud 55 on the outside of the register when it is desired to spread the rollers for threading the paper sheets in the machine before starting its operations.

The master gear 44 drives the pinion 56 on the stud 57 carried by the side wall of the register. Also fixed to this stud is the gear 58 which in turn drives the gear 59. This gear is mounted on the lower roller ejecting sleeve 60. This sleeve is loosely mounted upon the lower roller shaft 61 that is journaled in the side walls of the register. A spacing sleeve 62 mounted upon the shaft 61 to turn with it by reason of the pin 63 spaces the paper driving sleeve 60 laterally against the pin sleeve 64 which is attached by the stud 65 to the shaft 61. The sleeve 60 is provided with an enlarged knurled sleeve 66 for engaging the under side of the paper. The gear 59 drives the gear 67 of the upper roller 68. This roller is carried at either end by the lifting plates 51. The projecting ends of the roller fit loosely in the openings 69 in the side walls 1 and 2 of the register. This upper roller

is provided with a cooperating knurled sleeve 70 for engaging the upper surfaces of the sheets opposite the knurled sleeve 66 of the knurled roller.

The upper roller is cut away as at 71 to accommodate the aligning pins 72 which are carried by the aligning pin sleeve 64 mounted on the lower roller shaft 61. The central portion of the upper roller is enlarged as at 73 so as to hold the sheets in position intermediate the edges thereof and between the pins 72.

The upper roller is provided with a knurled sleeve for driving the paper designated 74 corresponding to the sleeve 70 and superimposed above and cooperating with the lower knurled sleeve 75 which is carried upon the loose sleeve 76 mounted on the lower roller shaft 61.

This upper roller is provided with a gear 77 that meshes with the gear 78 of the sleeve 76. Thus, the upper roller and the lower roller ejecting sleeves are driven from a common source of power and turn synchronously, the lower ejecting sleeves being driven from the upper ejecting roller.

The pin bearing sleeve 64 with its pin 72 are driven at a slower rate independently of the ejecting mechanism through the gear 79 mounted on the shaft 61. This gear derives its source of power from the handle shaft 42 but through a separate train of gears. The shaft 42 carries on the right hand side of the machine, as it is viewed from the rear, a pinion 80 which meshes with a large intermediate gear 81 carried on the stud 82 on the side wall of the register. This intermediate gear 81 meshes with the gear 79 which in turn drives the lower roller shaft 61.

The rotation of the shaft 50 is further resisted by the spring 83 which is connected to an arm 84 depending therefrom. This arm is caused to normally rest against the floor 85 of the side wall of the register. The spring 83 is attached to the side wall of the register at 86.

This construction can be seen in Figure 6 which has just been discussed in connection with the driving mechanism for the pins.

It will be noted that the pin driving mechanism travels at a slower rate than that of the paper ejecting mechanism.

The reason for this is that when the parts are as shown in Figure 13 at the beginning of the ejecting operation, it is desirable to free the paper sheets from the overhanging hook of the pin 72 which is designated 87 so that the downward movement of this hook 125 with the pin will not catch the paper and tear it.

The rear end of this pin is sloped as at 88. The upper surface of the pin is therefore arcuate so that as the paper rollers 130

feed the paper sheets faster than the movement of the pin, the sheets can be slipped up over the back of the pin and moved horizontally beyond the pin before the hook 5 87 can engage the forward edges of the holes of the sheets and tear the sheets.

It will be noted that the arcuate upper surfaces of these pins merge into the surface of the pin sleeve 64 so there is no obstacle to 10 pulling the paper forward over the backs of the pins.

The overhanging ledges 87 also act as a holding means when the paper is pulled upwardly to tear it off after the sheets have 15 been ejected when the parts are in the position shown in Figure 13. The pins at no time prevent the sheets from moving forwardly and do not in any way stop the sheets in their forward movement. They simply 20 align the sheets and assist in positioning the sheets as to any backward movement of the sheets but do not disturb the feeding. do not stop the feeding nor interrupt it in any way.

25 The holes in the sheets are designated 89. The master gear 44 is prevented from backward movement by the pawl 90.

The cover 6 is provided with a hood 91 for enclosing the rollers and has, on either 30 side of the front of this hood, depending eyes 92 for receiving the locking hooks 93 which are connected to the shaft 94 that is pivoted in the side walls of the register. This shaft 94 is provided with an operating 35 button 95 on the outside of the register for unlocking these locking hooks 93.

The hooks are maintained yieldingly in locking position by the spring 96 connected to the side wall of the register at 97 and to 40 an arm 98 which in turn is connected to the shaft 94. This arm 98 rests upon the shaft 50 as a stop. The rearward movement of the locking fingers 93 may be prevented by the positioning of the bell crank 99 45 which is pivoted on the register at 100. This bell crank has one arm adapted to engage the back of the lock 93 and have the other arm engaged by the lock 101 when it is in locked position.

50 The forward end of the cover 6 where it is formed in the hood 91 overlaps the rear end of the cover from the storage compartment holding it in locked position. Such storage cover lid is designated 13.

55 *Method of operation.*

When the handle is actuated with the parts in the position shown in Figure 10 the ejecting rollers travel at a greater speed 60 moving the sheets faster than the pins 72 over the back of the arcuate tops of the pins and continue this operation of ejection until the cam 45 engages the cam arm 46, which, in turn, engages the arm 49 rotating 65 the cam shaft 50, elevating the upper

roller shaft which results in the cessation of the ejecting operation of the paper by the upper ejecting roller and the lower ejecting roller sleeves 60 and 76. But, as the shaft 61 continues to turn, it brings the pins 72 70 into position so that they project through the holes 89 of the paper, as in Figure 12, and align the paper while it is loose against the gentle tension of the rear spring fingers 75

The rollers then are allowed to drop down by the position of the cam 45, the sheets are again clamped and held in writing position.

It will be noted that the cam 45 by its position will determine the point of rendering the rollers inoperative for ejecting purposes. The substitution of gears will determine the relative speeds and lengths of throw and times of alignment so that the machine is a universal one for different lengths of paper and different widths.

It will be understood that I desire to comprehend within my invention such modifications as may be necessary to adapt it to varying conditions and uses.

Having thus fully described my invention, what I claim as new and desire to secure by Letters Patent, is:

1. In an autographic register having a 95 plurality of superimposed sheets with spaced perforations, means to eject the sheets, means to render the ejecting means inoperative, and means having an overhanging ledge to align the sheets shaped to engage the forward walls of the apertures in the sheets only.

2. In an autographic register having a 105 plurality of superimposed sheets with spaced perforations, means to eject the sheets, means to render the ejecting means inoperative, means to align the sheets shaped to engage the forward walls of the apertures in the sheets only, and means for driving the ejecting means at a greater speed than the aligning means to free the sheets from the aligning means upon the start of a new cycle of operations.

3. In an autographic register having a 115 plurality of superimposed sheets with spaced perforations, means to eject the sheets, means to render the ejecting means inoperative, means to align the sheets shaped to engage the forward walls of the apertures in the sheets only, means for driving the ejecting means at a greater speed than the aligning means to free the sheets from the aligning means upon the start of a new cycle of operations, and common means for driving the aligning means and the ejecting means 120 at their respective predetermined speeds.

4. In an autographic register having a 125 plurality of superimposed sheets with spaced perforations, means adapted to engage said sheets in clamped arrangement to 130

5. In an autographic register having a plurality of superimposed sheets with spaced perforations, means adapted to engage said sheets in clamped arrangement to eject them, rotary means to be projected into said sheets through the apertures to align them when the sheets are free from the ejecting means, means to free the sheets from the ejecting means while they are being aligned, and means to operate said respective ejecting and aligning means at different rates of speed.
6. In an autographic register having a plurality of superimposed sheets with spaced perforations, ejecting means comprising superimposed rollers having paper engaging surfaces, and aligning pins carried in one of said rollers, said pins having forward surfaces vertically disposed for engaging with the forward margins of the apertures of the paper, and an arcuate upper surface extending downwardly and rearwardly merging at its rear end into the pin supporting roller so that there is no rear shoulder for obstructing the movement of the paper by the pin, and an overhanging lip on the forward wall of the pins, said lip upper surface being carried out in the same arcuate path as the remainder of the top of the pin.
7. In an autographic register having a plurality of superimposed sheets with spaced perforations, aligning means consisting of aligning pins having projecting front engaging surfaces for engaging said sheets in the front parts of the perforations, the top of said aligning means being formed in an arcuate surface.
8. In an autographic register having a plurality of superimposed sheets with spaced perforations, aligning pins adapted to be projected through the apertures in said paper, said pins being formed with a shoulder on the forward side and an arcuate upper surface which merges into the rear wall of the pin below the paper so that no rear shoulder is formed.
9. In an autographic register having a plurality of superimposed sheets with spaced perforations, ejecting means comprising superimposed rollers having paper engaging surfaces, and aligning pins carried in one of said rollers, said pins having forward surfaces vertically disposed for engaging with the forward margins of the apertures in the paper, and an arcuate upper surface extending downwardly and rearwardly merging at its rear end into the pin supporting roller so that there is no rear shoulder for obstructing the movement of the paper by the pin.
10. In an autographic register having a plurality of superimposed sheets with spaced perforations, ejecting means comprising superimposed rollers having paper engaging surfaces, and aligning pins carried in one of said rollers, said pins having forward surfaces vertically disposed for engaging with the forward margins of the apertures of the paper, and an arcuate upper surface extending downwardly and rearwardly merging at its rear end into the pin supporting roller so that there is no rear shoulder for obstructing the movement of the paper by the pin, and an overhanging lip on the forward wall of the pins, said lip upper surface being carried out in the same arcuate path as the remainder of the top of the pin.
11. In an autographic register having a plurality of superimposed sheets with spaced perforations, superimposed rollers adapted to eject the paper when in engagement therewith, aligning pins carried by one of said rollers, means for spreading said rollers at intervals, means for bringing aligning pins into the apertures of the paper during said intervals, said pins having shoulders for engaging the forward walls of the apertures of the paper only, and an arcuate upper surface so that the paper will slide over the tops of the pins from the back of the pins forwardly.
12. In an autographic register having a plurality of superimposed sheets with spaced perforations, superimposed rollers adapted to eject the paper when in engagement therewith, aligning pins carried by one of said rollers, means for spreading said rollers at intervals, means for bringing aligning pins into the apertures of the paper during said intervals, said pins having shoulders for engaging the forward walls of the apertures of the paper only, and arcuate upper surface so arranged as to permit the paper to slide over the tops of the pins from the back of the pins forwardly, and overhanging forwardly projecting lips on said pins, and means to drive said pins at a lesser rate of speed than said rollers whereby the paper can be moved off of said pins when once aligned so as not to be caught by the pins as the pins are moved out of the apertures in the paper after aligning has taken place.
13. A new article of manufacture for use as an aligning pin in an autographic register comprising a cylindrical body having a pin therein with an arcuate upper surface with a shoulder formed on the forward side

of the pin and no shoulder on the rear side of the pin.

14. A new article of manufacture for use as an aligning pin in an autographic register comprising a cylindrical body having a pin therein with an arcuate upper surface with a shoulder formed on the forward side of the pin and no shoulder is left on the rear side of the pin where it can engage the paper, and an overhanging arcuate lip on the forward side of the pin continuing the arcuate upper surface of the pin.

15. In an autographic register, having a plurality of superimposed sheets with spaced 15 perforations, operating means, a lower roller shaft, a pin sleeve and aligning pins carried thereby, paper ejecting sleeves carried by said shaft loosely thereon, an upper roller shaft having paper ejecting surfaces, means 20 to drive said upper roller shaft, means to drive the lower ejecting paper sleeves from the upper roller shaft, and means to independently drive the lower roller shaft, the pins and the pin sleeve.

16. In an autographic register having a plurality of superimposed sheets with spaced perforations, a lower roller shaft, a pin sleeve and aligning pins carried thereby, paper ejecting sleeves carried by said shaft 25 loosely thereon, an upper roller shaft having paper ejecting surfaces, means to drive said upper roller shaft, means to drive the lower ejecting paper sleeves from the upper roller shaft, means to independently drive the 30 lower roller shaft, the pins and the pin sleeve at different rates of speed from that of the paper ejecting sleeve.

17. In an autographic register having a plurality of superimposed sheets with spaced 40 perforations, operating means, a lower roller shaft, a pin sleeve and aligning pins carried thereby, paper ejecting sleeves carried by said shaft loosely thereon, an upper roller shaft having paper ejecting surfaces, means 45 to drive said upper roller shaft, means to drive the lower ejecting paper sleeves from the upper roller shaft, and means to independently drive the lower roller shaft, the pins and the pin sleeve, and means to render the paper driving means inoperative at 50 predetermined intervals while the pins are entering and aligning the sheets.

18. In an autographic register having a plurality of superimposed sheets with spaced 55 perforations, operating means, a lower roller shaft, a pin sleeve and aligning pins carried thereby, paper ejecting sleeves carried by said shaft loosely thereon, an upper roller shaft having paper ejecting surfaces, means 60 to drive said upper roller shaft, means to drive the lower ejecting paper sleeves from the upper roller shaft, and means to independently drive the lower roller shaft, the pins and the pin sleeve, means to render the paper 65 driving means inoperative at predetermined intervals while the pins are entering and aligning the sheets.

mined intervals while the pins are entering and aligning the sheets, and means to cause the reclamping of the paper ejecting means after the sheets have been aligned.

19. In an autographic register having a plurality of superimposed sheets with spaced 70 perforations, operating means, a lower roller shaft, a pin sleeve and aligning pins carried thereby, paper ejecting sleeves carried by said shaft loosely thereon, an upper roller shaft having paper ejecting surfaces, means to drive said upper roller shaft, means to drive the lower ejecting paper sleeves from the upper roller shaft, means to independently drive the lower roller 75 shaft, the pins and the pin sleeve, means to render the paper driving means inoperative at predetermined intervals while the pins are entering and aligning the sheets, and means to cause the reclamping of the paper 80 ejecting means after the sheets have been aligned, and means for actuating the paper ejecting means at a faster rate than the pin aligning means to free the sheets from the pins after the sheets have been 85 aligned before the pins pass out of the sheets to prevent the pins from tearing the sheets.

20. In an autographic register, a lower roller shaft, means for driving said shaft, 90 paper ejecting sleeves loosely carried on said shaft, a pin sleeve turning with said shaft, pins therein having aligning shoulders on the forward sides thereof, and arcuate surfaces proceeding backwardly 95 and merging into the pin sleeve so that there is no shoulder at the rear of the pins, an upper roller shaft having paper ejecting surfaces with cutaway portions for 100 accommodating said pins, means for driving said upper roller shaft from the common power means, and means for driving the lower paper ejecting sleeves from the upper roller shaft.

21. In an autographic register having a 110 plurality of superimposed sheets with spaced perforations, a lower roller shaft, means for driving said shaft, paper ejecting sleeves loosely carried on said shaft, a pin sleeve turning with said shaft, pins therein having aligning shoulders on the forward sides thereof, and arcuate surfaces proceeding backwardly 115 and merging into the pin sleeve so that there is no shoulder at the rear of the pins, an upper roller shaft having paper ejecting surfaces with cutaway portions for accommodating said pins, means for driving said upper roller shaft from the common power means, and means for driving the lower paper ejecting sleeves from the upper roller shaft, and means actuated by the common power 120 means for rendering the paper ejecting means of the upper roller shaft and the lower ejecting sleeves inoperative while the 125

pins are aligning the sheets through the apertures thereof.

22. In an autographic register having a plurality of superimposed sheets with spaced perforations, a lower roller shaft, means for driving said shaft, paper ejecting sleeves loosely carried on said shaft, a pin sleeve turning with said shaft, pins therein having aligning shoulders on the forward sides thereof, and arcuate surfaces proceeding backwardly and merging into the pin sleeve so that there is no shoulder at the rear of the pins, an upper roller shaft having paper ejecting surfaces with cutaway portions for accommodating said pins, means for driving said upper roller shaft from the common power means, and means for driving the lower paper ejecting sleeves from the upper roller shaft, and means actuated by the common power means for rendering the paper ejecting means of the upper roller shaft and the lower ejecting sleeves inoperative while the pins are aligning the sheets through the apertures thereof, and means for actuating the paper ejecting means at a greater rate of speed than the pins are moved for freeing the paper sheets from the pins.

23. In an autographic register having a plurality of superimposed sheets with spaced perforations, a lower roller shaft, means for driving said shaft, paper ejecting sleeves loosely carried on said shaft, a pin sleeve turning with said shaft, pins therein having aligning shoulders on the forward sides thereof, and arcuate surfaces proceeding backwardly and merging into the pin sleeve so that there is no shoulder at the rear of the pins, an upper roller shaft having paper ejecting surfaces with cutaway portions for accommodating said pins, means for driving said upper roller shaft from the common power means, and means for driving the lower paper ejecting sleeves from the upper roller shaft, and means actuated by the common power means for rendering the paper ejecting means of the upper roller shaft and the lower ejecting sleeves inoperative while the pins are aligning the sheets through the apertures thereof, and means for actuating the paper ejecting means at a greater rate of speed than the pins are moved for freeing the paper sheets from the pins, said pins being so arranged as to have forwardly engaging shoulders and no shoulders on the rear thereof to obstruct the movement of the paper over the tops and rear of the pins.

24. In an autographic register, ejecting means, means to render said ejecting means inoperative, means to return said ejecting means to operative position, means to actuate the ejecting means, aligning means comprising aligning pins having front shoulders for insertion in the apertures to engage

the front walls thereof and smooth rear and upper surfaces over which the paper sheets may slide from the rear to the front without obstruction.

25. In an autographic register, ejecting means for a plurality of superimposed sheets of paper, consisting of a roller and a pair of sleeve members operatively connected to the roller, a shaft loosely supporting said sleeve member and a paper aligning means affixed to said shaft, and means for operating said ejecting means and said aligning means at different rates of speed.

26. In an autographic register, ejecting means for a plurality of superimposed sheets of paper, consisting of a movable roller and a pair of sleeve members operatively connected to the roller, a shaft loosely supporting said sleeve members, a paper aligning means affixed to said shaft, means for operating said ejecting means and said aligning means at different rates of speed, and means to move said roller from the sleeves to stop the ejecting operation for the aligning operation.

27. In an autographic register, ejecting means for a plurality of superimposed sheets of paper having aligned holes therein, said ejecting means consisting of a roller and a pair of sleeve members operatively connected to the roller, a shaft loosely supporting said sleeve members, a sleeve affixed to said shaft between said sleeve members, said sleeve having forwardly projecting hole-engaging pins thereon, and means for rotating said ejecting means and said shaft at different rates of speed, whereby after the pins engage the holes in the sheets and align them the paper will be advanced more rapidly than the pins so that the paper will slip from the pins without being engaged by the forward ends of the pins.

28. In an autographic register, ejecting means for a plurality of superimposed sheets of paper having aligned holes therein, said ejecting means consisting of a movable roller and a pair of sleeve members operatively connected to the roller, a shaft loosely supporting said sleeve members, a sleeve affixed to said shaft between said sleeve members, said sleeve having forwardly projecting pins thereon, means for rotating said ejecting means and said shaft at different rates of speed, and means in each cycle of operation to move the roller from the sleeve members to stop the ejecting of the paper, whereby on a continual operation the pins engage in the holes of the sheets of paper to align them, and on the beginning of another cycle of operation the ejecting means are caused to engage the sheets of paper and advance them so that the paper will slip from said pins.

In testimony whereof, I affix my signature.
